UNITED STATES PATENT OFFICE.

NEWTON ABRAHAM COOPER, OF BACK CREEK VALLEY, VIRGINIA.

BUCKLE.

SPECIFICATION forming part of Letters Patent No. 324,921, dated August 25, 1885.

Application filed April 27, 1885. (No model.)

To all whom it may concern:

Be it known that I, NEWTON A. COOPER, a citizen of the United States, residing at Back Creek Valley, in the county of Frederick 5 and State of Virginia, have invented a new and useful Improvement in Buckles, of which the following is a specification, reference being had to the accompanying drawings.

My invention relates to buckles, and it has 10 for its object to provide a device of this character whereby a strap may be readily and quickly lengthened and shortened, to provide a buckle which will firmly and securely hold the strap in position, one that will be simple 15 in its construction, strong and durable, and cheap to manufacture.

With these ends in view, the invention consists in the combination, with a frame, of a pivoted plate carrying pins or tongues to 20 engage the strap.

The invention further consists in the improved construction and combinations of parts hereinafter fully described, and pointed out in the claims.

25 In the drawings, Figure 1 is a perspective view of a buckle constructed in accordance with my invention, and showing the same applied. Fig. 2 is a longitudinal vertical section, and Fig. 3 is a plan view.

30 In the accompanying drawings, in which like letters of reference indicate corresponding parts in all the figures, A represents the frame, composed of the side bars, *a*, connected on their upper and lower sides by cross-bars *b c*. The said frame A may be sewed, riveted, or otherwise firmly secured to a strap or other object, such as a pair of suspenders. Upon the upper side of the frame is hinged to one 35 end thereof a plate, B, which is provided with downwardly-extending pins or tongues C, which are adapted to pass through openings formed in the top and bottom cross-bars connecting the sides of the frame, and through the openings in the strap D, which 40 is passed through said buckle. It will be seen that by lifting the plate B from engagement with the strap D the same may be lengthened and shortened.

45 At the end of the frame A at which the free end of the pivoted plate B is located, and upon the upper side of said frame, is provided

a pivoted catch, E, having a recess at its free end, which recess is adapted to engage a pin, F, projecting upwardly from the upper side of the frame A. It will thus be seen that 55 when the pins or tongues are in engagement with the openings in the cross-bars of the frame and with the openings in the strap, and the catch in engagement with the pin F, the said plate B will be held against movement, thus preventing the possibility of the strap D becoming detached.

The before-described buckle is simple in its construction, strong and durable, may be manufactured and supplied at a slight cost, and 65 by its use a strap may be readily and quickly adjusted with but little trouble.

I am aware of the patent to Welden and Royee, No. 216,003, dated May 27, 1879, and do not claim anything shown therein. In 70 this patent there is no inclosing-frame for the two straps at the point of connection. Another feature of difference is the swinging catch, which, in my improvement, extends transversely across the end of the hinged 75 plate, and is independent therefrom. By this means the catch will not interfere with the plate when adjusting the straps. When the catch is parallel with the plate, it must be extended out at right angles, and will be in the 80 way when adjusting the straps. When the catch extends across the end of the plate, it will effectually resist all upward tendency of the latter to become loosened. When it is arranged parallel with the plate, it will be 85 seen that any considerable tension on the connection will cause the plate and catch to spring upward and become loosened or detached. By my construction the catch will serve to hold the hinged plate down and yet allow a 90 ready detachment of the parts. The catch, when swung aside, will not be in the way of the operator. Again, the inclosing-frame enables the device to be used for a special purpose—*i. e.*, for suspenders, where it is desired 95 that the connection be concealed from view.

Having fully described my invention, what I claim as new, and desire to secure by Letters Patent, is—

As an improvement in buckles, the rectangular inclosing-frame A, the plate B, hinged at one end to the upper face of the frame,

tongues C, carried by the plate and passing through the frame and straps, a swinging catch, E, pivoted to the frame on one side of the plate and extending transversely over the end thereof, and a stud, F, on the other side of the frame, adapted to be engaged by the catch, as and for the purpose set forth.

In testimony that I claim the foregoing as my own I have hereto affixed my signature in presence of two witnesses.

NEWTON ABRAHAM COOPER.
